UNITED STATES PATENT OFFICE

HARRY G. EVITT, OF BALTIMORE, MARYLAND

RADIATOR SHIELD

Application filed September 28, 1929. Serial No. 395,873.

This invention relates to shields for radiators or other devices from which convection currents arise and it has for its object the provision of a device of the class described adapted to fit over radiators of different length and having means adapted to block or substantially close the space between the radiator and wall, adjustable to fit spaces of various widths.

10 Other objects of the invention will appear as the following description of a preferred embodiment of the invention proceeds.

In the drawings in which similar characters of reference denote like parts,

15 Fig. 1 is a perspective view of the invention.

Fig. 2 is a cross section taken along the line 2—2 of Fig. 1 showing the invention applied to a radiator and in contact with an 20 adjacent wall.

Before discussing in detail the several figures it may be stated that a common objection to radiators as at present installed is that the current of heated air rising between the 25 radiator and adjacent wall carries with it dust from the floor which is deposited on the surface of the wall above the radiator or on window curtains or on the ceiling above. Furthermore it is known that where the current 30 of heated air rises vertically above the radiator, there is poor distribution of heat within the room since the heated air accumulates near the ceiling, without mixing readily with the bulk of the air within the room.

35 It is already known to provide radiators with deflecting shields for throwing the heated air current toward the center of the room and it is also known to close the space between the radiator and the wall so as to prevent or reduce the passage of the air current 40 from behind the radiator against the wall.

Since radiators are of various length however it has been practically impossible heretofore without wasteful overstocking to provide shields or deflectors of a size to fit all 45 lengths of radiators.

Since the space between the radiator and the wall also varies for different radiators it 50 has been uneconomical to carry in stock ra-

diator shields having rear panels or flaps of the various widths required.

By combining in a single shield or deflector features of adjustability by means of which it may fit all lengths of radiators, and likewise, features of adjustability of the rear flap or panel by which it may be made to close any size of space, as is done in the present invention, not only can the shield or deflector be economically produced but its construction 55 simplified, and the work of installing the 60 same facilitated.

The radiator shield of the present invention as shown, comprises a pair of cooperating telescoping sections 1 and 2. These sections are preferably each formed like an inverted trough with front flanges 3 and 4 and rear flanges 5 and 6. The front and rear flanges enable the shield or deflector to be fitted upon the top of the radiator without risk of its falling off while, since the sections are telescoping they may be pushed together or drawn out in order properly to fit the radiator to which they are applied. The front and rear flanges of the section 4 are 70 bent over as shown at 7 and 8 to form channels or tracks in which the edges of the section 1 slide, the latter being thus retained by the former section. The two sections are 75 provided with end flanges 9 and 10.

The front flanges 3 and 4 are preferably provided with series of perforations 11 and 12 the main object of which is to afford an escape for the heated air, into the room. The slots also perform the function of assisting 80 in holding the two sections together, any suitable bolting means 15 being passed through any two slots which may be in registry when the shield or deflector is at its proper length.

One of the striking features of the invention is the means utilized to furnish an adjustment in connection with the rear flap or flange for permitting it to be accommodated to any width of space between wall and radiator which it may be desired to close. This adjusting means consists of a longitudinal linear weakened region 14 such as a score mark formed on the rear flap. Along this 90 mark or weakened region the lower portion of 95 100

the flap may be hingedly bent backwards a suitable distance to form a closure for the said space, the angle of the flap being determined to suit the width of the space.

5 The score marks along the two sections are in line with one another so that the telescoping of the sections by which their length is determined also determines the length of the angularly bent portion of the flaps.

10 It is to be understood that in the present illustrative embodiment of the invention the structure has been reduced to its elemental form, but that in practice the invention may be carried out equally well in more ornate and complicated forms of shield or deflector.

15 It is likewise to be understood that the invention is not confined to use with heating radiators but that it is applicable to any device from which convection currents, hot or cold, may emanate.

20 While I have described what I believe to be a preferred form of the invention it is to be understood that numerous variations in 25 the constructional details may be resorted to without transcending the invention provided that they can be construed to be within the terms of the appended claims.

25 What I claim is:

30 1. A shield for radiators adapted to fit over the top of a radiator, comprising cooperating telescoping sections, each in the form of an inverted channel and each having a front flange and a back flange, a flap depending from the back flange to close the space between the radiator and an adjacent wall, the front flange and the flap of one section having turned edges in which the edges of the other section slide, said flap being adjustable by bending to fit the said space between the radiator and wall, said front flanges being each formed with a series of apertures, the apertures of one series registering with those of another series when said sections are 35 in positions of adjustment.

40 2. A shield for radiators adapted to fit over the top of a radiator and to close the space between the radiator and an adjacent wall, comprising relatively adjustable telescoping 45 channel sections each having a front and a rear flange, each said rear flange having a depending back flap, said back flaps being each formed with longitudinal linear weakened regions about which the lower portions of said back flaps may be hingedly bent, said longitudinally weakened regions, for said sections, being in alinement, and means for holding the sections in telescoping relation, the channel construction and rear flap serving to hold the shield in position enclosing the upper portion of the radiator with the rear flap bearing against the wall.

50 3. A shield for radiators adapted to fit over the top of a radiator, comprising cooperating telescoping sections, each in the form

55 of an inverted channel and each having a front flange and a back flange, a flap depending from the back flange to close the space between the radiator and an adjacent wall, the front flange and the flap of one section having turned edges in which the edges of the other section slide, said flap being adjustable by bending to fit the said space between the radiator and wall, and said front flanges each having a series of air outlet apertures.

60 Signed by me at Baltimore, Maryland, this 18th day of September, 1929.

HARRY G. EVITT.
